UNITED STATES PATENT OFFICE.

WILLIAM ARTHUR CARLETON, OF GOVERNORS ISLAND, NEW YORK.

EYE-SHADE.

1,401,758.

Specification of Letters Patent. Patented Dec. 27, 1921.

Application filed December 20, 1920. Serial No. 432,003.

To all whom it may concern:

Be it known that I, WILLIAM ARTHUR CARLETON, a citizen of the United States, and resident of Governors Island, New York, 5 have invented a new and Improved Eye-Shade, of which the following is a full, clear, and exact description.

In connection with eye shades it is a well appreciated fact that considerable difficulty 10 has been experienced in constructing a device of this character, which would not alone prevent the glare of light rays falling upon the eyes of the wearer from a line substantially in front and above him, but would 15 also preclude any danger of what might be termed "side glare."

Also these devices have, when not in use, or while being transported, presented certain difficulties in that, due to the curvature 20 of their bodies they did not lend themselves readily to being sent through the mail, as for instance, in the nature of an advertisement, or being carried in the pocket of the person using the same.

Having this in mind, I have now constructed an eye shade, which will primarily be capable of being put on the market at an extremely low figure.

A further object of my invention is the 30 provision of a device of this character which will preclude "side glare" thus avoiding a common objection to devices of this nature.

A still further object of my invention is the construction of an eye shield which may 35 readily be folded to permit of its being carried in the pocket or sent in an envelop.

Further objects of my invention will appear in the annexed specification and drawings, which latter present one practical embodiment of my invention, and in which—

Figure 1 is a perspective view of my device in applied position upon the head of a wearer.

Fig. 2 illustrates the eye shade in extended 45 position, and

Fig. 3 shows the same when folded preparatory to being inserted into an envelop so as to be capable of being placed in a pocket.

In these views the reference numeral 5 in-

dicates the body of the shade which is provided with a cut out portion 6 conforming to the contour of the forehead.

Tabs 7 may conveniently form an integral portion of the body 5, and are positioned adjacent the side edges of this body. The tabs 55 are capable of a hinged or swinging connection along the lines 8 which may be accomplished by weakening the material of which the shade is constructed, at this point.

The shade may be made of any desirable 60 material, but is preferably constructed of a heavy card or paper, so as to be capable of being put on the market at an extremely low figure, and a conventional resilient strip 65 9 may extend between and be connected to points adjacent the outer edges of the tabs 7.

Thus it will be appreciated, reference being had to Fig. 1, that I have provided an eye shade in which the body portion 5 will serve to protect the eyes of the wearer from 70 front and downward glare, the tabs 7 preventing side glare from reaching the eyes of the person to the head of whom this shade is applied, the shade being retained in this 75 position by virtue of the strip 9 encircling the head of the wearer.

Obviously by virtue of the construction provided, a device may readily be folded to be placed in an envelop, or the pocket of the wearer, and it is to be noted that the cut-out portion 6 terminates at a point short of the lines of folding 8, so that the shoulder 10 is provided which will serve to space the tabs 7 from the head of the wearer and avoid disagreeable pressure.

Obviously numerous modifications of structure might readily be resorted to without in the least departing from the spirit of my invention, which I claim as—

An eye shade, including a body portion, and tabs swingingly connected to and forming a continuation of the side edges of said body portion, said body being formed with a cutout portion in one of its longitudinal edges, said cutout portion terminating short 90 of the points of swinging connection of said tabs with said body portion.

WILLIAM ARTHUR CARLETON.
